No. 37,296.

Patented January 17, 1905.

UNITED STATES PATENT OFFICE.

WILLIS J. BOYLE, OF LOS ANGELES, CALIFORNIA.

DESIGN FOR A STOVE.

SPECIFICATION forming part of Design No. 37,296, dated January 17, 1905.

Application filed November 21, 1904. Serial No. 233,740. Term of patent 14 years.

To all whom it may concern:

Be it known that I, WILLIS J. BOYLE, a citizen of the United States, residing at Los Angeles, in the county of Los Angeles and State of California, have invented a new, original, and ornamental Design for Stoves, of which the following is a specification, reference being had to the accompanying drawing, forming part thereof.

The figure is a side elevation of a stove, showing my new design.

What I claim as new, and desire to secure by Letters Patent, is—

The ornamental design for a stove, as shown.

WILLIS J. BOYLE.

In presence of—

ARTHUR P. KNIGHT,
JULIA TOWNSEND.
